1,713,656

UNITED STATES PATENT OFFICE.

WALTER F. HEROLD, OF UPPER MONTCLAIR, NEW JERSEY, ASSIGNOR TO THE BASSICK COMPANY, OF BRIDGEPORT, CONNECTICUT, A CORPORATION OF CONNECTICUT.

CASTER.

Application filed January 24, 1927. Serial No. 163,948.

The present invention relates to improvements in casters, and has for an object to provide a socket and pintle structure, in which pintle retaining means is provided at the 5 base of the socket, so that the latter may be of any desired size or shape, without respect to the pintle shape or diameter, and further in which the retaining means is disposed entirely within the base in non-rotatable relation, and is adapted to so cooperate with the 10 pintle that it will be free of gripping contact therewith during normal use of the caster. In particular, it is proposed to provide a pintle retaining member in the form 15 of a flat spring adapted for lateral expansion and contraction, so that it will occupy a very small space within the base, without materially increasing its depth, and which may be connected to the base without the necessity 20 of providing separate securing or attaching means. Heretofore, fixed pintle retaining spring means have been provided in the form of a split tubular structure extending into the 25 socket shell, and adapted to engage beneath a head or enlargement on the pintle, but these were subject to distortion, were difficult to manufacture, and required a special size or shape in the shell structure.

A further object is to provide pintle retaining means in the form of a sheet metal spring adapted to be economically formed by blanking and stamping operations.

With the above and other objects in view, embodiments of the invention are shown in 35 the accompanying drawings, and these embodiments will be hereinafter more fully described with reference thereto, and the invention will be finally pointed out in the claim.

40 In the drawings:—

Fig. 1 is a vertical sectional view of a socket, according to one embodiment of the invention, and showing the caster in place therein;

Fig. 2 is a bottom plan view of the socket;

Fig. 3 is a side elevation, partly in section, of a modified form of the invention;

Fig. 4 is a horizontal sectional view, taken along the line 4—4 of Fig. 3;

Fig. 5 is a vertical sectional view thereof, taken along the line 5—5 of Fig. 3, and showing the caster pintle in place therein;

Fig. 6 is a vertical sectional view of a further modified form of socket, according to the invention, and showing the caster pintle in place therein;

Fig. 7 is a top plan view thereof; and Fig. 8 is a bottom plan view.

Similar reference characters indicate corresponding parts throughout the several figures of the drawings.

Referring to the drawings, and more particularly to Figs. 1 and 2 thereof, the embodiment of the invention shown therein is particularly adapted for use with wood furniture legs, and comprises a tubular socket 65 shell 10 having a top portion 11 provided with a top pintle bearing 12 in the form of an inverted cone-shaped indenture. At its lower end the shell is crimped, as at 13, to form a shoulder against which the apertured socket 70 base 14 is secured by flanging over the lower edge of the shell, as at 15. In outwardly spaced relation to the shell the base is bent downwardly to form an annular wall 16, and at its outer edge the base is provided with an 75 upwardly bent flange 17 having serrations 17^a in its upper edge for driving into the wood leg.

The pintle retaining means consists of a flat spring ring 18 of sheet metal, split at 19, 80 and provided with projecting ears or lugs 20, 20, which are engaged in diametrically opposed slots 21, 21, provided in the wall 16, the ring being thus retained and held against relative rotation with respect to the socket. 85 Obviously this type of spring ring may be readily sprung or snapped into place by first compressing it.

The detachable caster consists of the usual horn 22 having a caster wheel 23 rotatably 90 carried therein upon an axle 24, and having a pintle 25 secured in its upper transverse portion, the lower end of the pintle being provided with a flange 26 engaging the upper surface of the horn. At the upper end of the pintle there is provided a cone-shaped recess 27 95 adapted to engage the top center bearing 12. The pintle is provided at its lower portion with an enlarged diameter portion 28, provided with an annular groove 29, and above 100 the groove there is provided a portion 30, tapering from the portion 28 to the upper smaller diameter portion of the pintle. The diameter of the pintle is such that the upper portion will pass freely through the spring 105 ring 18, while the tapered portion 30 will expand the ring, and as the pintle is pressed in to its full extent the ring will contract within the groove 29 in loose or non-frictional relation therewith, and the caster will thus be 110

held against dropping out of the leg. In its normal swiveling action while supporting the furniture, however, the pintle will be free of the ring, so that the latter will not be under tension.

In Figs. 3 to 5 I have illustrated a modified form of construction, particularly adapted for use in metal tubular legs, and comprising a frame member 31 formed of sheet metal bent upon itself and pressed to shape to provide a top bearing socket portion 32 having a center bearing 33 in the form of an indenture, pinched together ears 34 and 35 at diametrically opposite sides of said top portion, and side legs 36 and 37, shouldered adjacent said top portion, and pressed to form portions of a cylinder adapted to fit into the leg. At their lower ends the legs are flanged outwardly, as at 38 and 39, to form shoulders adapted to be disposed beneath the end of the leg, and bent downwardly and inwardly, as at 40 and 41, to clampingly engage the periphery of a circular base plate or disc 42. This disc is centrally apertured, as at 43, to receive and provide a bottom bearing for the pintle, and at each side of said aperture parallel slots 44 and 45 are formed and the metal between the slots is pressed upwardly, so that the apertured portion is in raised relation, the ends of the pressed up portion, between the ends of the slots, being beveled and in concentric and spaced relation to the aperture.

The pintle retaining means consists of a sheet metal spring member 46, in the form of a fork, having its side portions of arcuate shape and providing an opening concentrically disposed within the aperture beneath the central raised portion of the base. The forward split end of the spring member is inserted and retained within the slot 44, while the other end extends through the slot 45 and is provided with a projecting portion 47 bent downwardly through a slot 48 in the base and secured by bending over upon the under surface of the base.

The caster and pintle construction is similar to that shown in Fig. 1, and its cooperation with the socket is substantially the same as described with reference to the first embodiment, the pintle having top bearing with the center bearing 33 and bottom bearing in the aperture 43, the pintle retaining spring means being loosely engaged within the groove 29.

In Figs. 6 to 8 I have illustrated a further modified form, adapted for use in wood legs, and comprising a tubular socket shell member 50 formed from flat sheet metal stock folded upon itself, and providing a top portion 51 including a top center bearing 52 in the form of an inverted cone-shaped indenture, the longitudinal meeting edges of the blank providing longitudinal seams 53 at

opposed sides of the socket member. At the base of the socket member there is provided an annular outwardly bent shoulder 54 and an annular downwardly bent flange 55. The base member 56, cupped up from sheet metal stock, is provided with an inwardly bent bottom flange 57 having a central pintle receiving aperture 58. At the upper edge of the cup there are formed spaced upwardly projecting prongs 59, and between these there are provided lug portions 60 adapted, as shown in Fig. 7, to be bent inwardly upon the upper surface of the shoulder 54 to secure the base to the socket member.

The pintle retaining means is mounted on the base member and consists of a flat sheet metal spring ring 61, split at 62, and provided at a point of its outer edge with a lug 63 inserted downwardly through a slot 64 in the base flange 57, and bent over upon the under surface to thereby secure the spring against relative rotation with respect to the socket. The caster and pintle construction is similar to that shown in Fig. 1, and its cooperation with the socket is substantially the same.

The aperture of the spring ring is of smaller diameter than the aperture 58 of the base and the enlarged portion 28 of the pintle, but is larger than that of the pintle groove 29, so that while it retains the pintle against dropping out, the same is free of any gripping contact with the ring.

I have illustrated and described preferred and satisfactory embodiments of the invention, but it will be obvious that changes may be made therein, within the spirit and scope thereof, as defined in the appended claim.

Having thus described my invention, what I claim and desire to secure by Letters Patent is:—

In a caster, or the like, the combination of a floor engaging element including a pintle having an annular recess in proximity to its base, and a pintle receiving element adapted to be secured to a furniture leg or the like and having an apertured pintle retaining base and annular laterally extending spring retaining pocket forming means surrounding said aperture, and a one-piece split spring member disposed in said pocket, including a portion securing it against rotation therein, and abutted at its upper side by said pocket and adapted for expansion and contraction in a plane substantially parallel to the plane of the base, said spring member adapted to be expanded by said pintle during insertion and upon complete insertion to contract into said annular recess in non-gripping untensioned relation therein.

Signed at Bridgeport, in the county of Fairfield, and State of Connecticut, this 18th day of January, 1927.

WALTER F. HEROLD.
